UNITED STATES PATENT OFFICE.

LEON K. BELCHER, OF NEW YORK, N. Y.

OIL-BURNER.

1,272,897.

Specification of Letters Patent.

Patented July 16, 1918.

Application filed December 31, 1917. Serial No. 209,710.

To all whom it may concern:

Be it known that I, LEON K. BELCHER, a citizen of the United States, residing at New York, in the county and State of New York, have invented certain new and useful Improvements in Oil-Burners, of which the following is a full, clear, and exact specification.

This invention relates to oil vapor burners, and one object is to simplify the construction of such burners by casting the same in an integral piece.

Another object is to improve the heating power of the burner and eliminate smoke by providing a blue flame. It is also the aim of this invention to provide means for regulating the size of the flame and thereby control the heat generated. A further object is to produce a burner with a plurality of flame jets, with means for cutting off the gas to one or more of the jets while one or more of the other jets are being used. Other objects will appear as the description proceeds.

The invention will be first hereinafter described in connection with the accompanying drawings, which constitute part of this specification, and then more specifically defined in the claims at the end of the description.

In the accompanying drawings, in which similar reference characters are used to designate corresponding parts throughout the several views:—

Figure 1 is an end elevation of a burner constructed substantially in accordance with this invention.

Fig. 2 is a section on the line II—II of Fig. 1, and

Fig. 3 is a section on the line III—III of Fig. 2.

Instead of the several pipes and connecting elbows generally used in constructing burners of this class, an integral casting 1 is used in this case, the same being approximately rectangular in shape with an upper horizontal portion 2, a lower horizontal portion 3, and vertical end portions 4 and 5. The upper horizontal portion 2 has two longitudinal bores 6 and 7 which are connected by a cross bore 8 at one end. The other end of the bore 6 communicates with a nipple 9 designed to be attached to any source of oil supply, while the other end of the

bore 7 communicates with a bore 10 in the end portion 5 of the casting 1. The lower horizontal portion 3 has a single longitudinal bore 11 which communicates with the bore 10.

The burners proper 12 are detachably connected to the under face of the upper horizontal portion 2 of the casting preferably by means of the sliding dove-tail joints 13 best illustrated in Fig. 3, which permits said burners to be removed for cleaning, repairing or adjustment. Each burner comprising a funnel shaped body member 14 having a horizontal annular flange 15 at its upper end, and a disk 16 to fit said flange and adjustably connected thereto by bolts 17. The upper face of the flange 15 is dished at 18, and the disk is correspondingly dished at 19 so that the faces thereof which are presented to each other are parallel. By means of the bolts 17 the space between the flange 15 and disk 16 may be varied to decrease or increase the size of the flame which in use is formed around the top of the burner. Each burner is arranged directly over an opening 20 in the lower portion 3 of the casting. These openings 20 communicate with the bore 11 and are directed upwardly so that the gas which issues therefrom is projected into the conical or funnel-shaped passage in the body member 14 of the burner. Owing to the shape of these passages the passage of the gas therethrough draws in air with it so that the flame which issues around the top of the burner from the space between the flange 15 and disk 16 is a smokeless blue flame capable of generating a maximum heat. This flame is positioned close below the upper portion 2 of the casting, thus insuring against waste of the heat generated.

In operation, the oil which is admitted at the nipple 9 passes through the bore 6 over the burners, and then back over them again through the bore 7. Both of these bores are filled with rods 21 which serve to break up the oil and greatly help in vaporizing it. From the bore 7 the vaporized fuel passes down through the bore 10 to the bore 11 from which it issues through the openings 20 to the burners.

A valve 22 is provided in the bore 11 between the openings 20, so that one burner may be used alone, the gas being cut off

from the other. Of course, this valve may be opened and both burners used together when desired.

When the oil supply is first turned on, a small quantity of inflammable material is placed in the bells 23 which are supported from the under face of the lower portion 3 of the casting. This inflammable material is ignited and the flame therefrom will act in place of the flames from the burners to vaporize the oil in the bores 6 and 7. The several bores on the casting are provided with removable plugs 24 at their ends to permit cleaning, the introduction of the filling rods 21, and other purposes.

The casting 1 preferably has depending portions 25 below the lower horizontal portion 3 for supporting the device in operative position. The bore 6 may be termed the gas generating chamber, and the bore 7 may be called the gas drying and expansion chamber, for the oil is vaporized in the bore 6 and is further dried and allowed to expand in the bore 7.

Having thus described my invention, what I claim as new and desire to secure by Letters Patent of the United States is:

1. An oil burner of the character described having a gas generating chamber, a burner having sliding interlocking connection with the under surface of the chamber, and means for supplying gas from said chamber to the burner.

2. An oil burner of the character described having a gas generating chamber, a burner

below said chamber, said burner comprising a conically bored body portion and a disk covering the same, said body portion and disk being dished and having their facing surfaces parallel, means for retaining the disk in spaced relation to the body portion for providing an annular opening for the flame, and means for supplying gas to the burner from the gas generating chamber.

3. An oil burner of the character described having a gas generating chamber, a burner below said chamber, said burner comprising a conically bored body portion and a disk for covering the same, sliding interlocking connection between the disk and the under surface of the generating chamber, adjustable means of connection between the disk and body portion for providing a variable annular opening for the flame, and means for supplying gas to the body portion of the burner from said generating chamber.

4. A burner comprising a body portion having a central bore, a disk covering the bore at the top of the body portion, and means for retaining the disk in spaced relation to the body portion for providing an annular flame opening around the top of the burner, said disk being dished over the bore, and the top of the body portion being correspondingly concaved for the purpose specified.

In testimony whereof I have signed my name to this specification.

LEON K. BELCHER.
